(57) **CLAIM**

The ornamental design for a bucketless handle, as shown and described.

DESCRIPTION

FIG. 1 is a perspective view of a bucketless handle;
FIG. 2 is a front elevational view of the bucketless handle of FIG. 1;

FIG. 3 is a rear elevational view of the bucketless handle of FIG. 1;

FIG. 4 is a top plan view of the bucketless handle of FIG. 1;
FIG. 5 is a bottom plan view of the bucketless handle of FIG. 1; and,

FIG. 6 is a left side elevational view of the bucketless handle of FIG. 1.

The right side elevational view of the bucketless handle of FIG. 1 is not shown because it is a mirror image of the left side elevational view of the bucketless handle of FIG. 1.

The ornamental design which is claimed is shown in solid lines in the drawings.

The broken lines in the figures show features of the bucketless handle that form no part of the claimed design.
